HARRY L. PELZER, OF HIGHLAND, INDIANA, ASSIGNOR TO SINCLAIR REFINING COMPANY, OF NEW YORK, N. Y., A CORPORATION OF MAINE

ART OF CRACKING AND COOKING HYDROCARBONS

Application filed February 19, 1929. Serial No. 341,214.

This invention relates to improvements in the combined vapor phase cracking of oils, such as gas oil or kerosene stocks, for the production of lower boiling oils, such as gasoline, and the coking of heavy oils, such as crudes, topped crudes, flux oils, other residual oils and the like. The combined operation of the invention is of special application in the handling of crude stocks or residual stocks the handling of which usually involves difficulties due to corrosion or the products of which are unusually refractory with respect to the usual refining operations, because of the character or quantity of sulphur compounds in the stock, for example; but, as will appear, the invention is, in certain aspects, of more general application.

This invention is, in certain aspects, an improvement in the operations described in my application Serial No. 340,996, filed February 18, 1929, which has matured into Patent No. 1,831,719 issued November 10, 1931.

In carrying out this invention, as in carrying out the invention of Patent No. 1,831,719 mentioned above, the hot vapor mixture from a vapor phase cracking operation, while still at a high temperature, is passed in intimate contact with a liquid oil mixture to be reduced to coke in a receptacle adapted to receive an accumulating charge of coke, this liquid oil mixture is coked in this receptacle by the heat of the hot vapor mixture from the vapor phase cracking operation, and the hot vapor mixture from this receptacle is discharged into and beneath the surface of a liquid body of oil in another receptacle in which it is subjected to a scrubbing operation.

According to this invention, the hot vapor mixture from the vapor phase cracking operation is first passed through a first and a second receptacle of a series in succession, a charge of oil being coked in the first receptacle and the hot vapor mixture from the first receptacle being subjected to a scrubbing operation in the second receptacle during this step in the operation, the hot vapor mixture from the vapor phase cracking operation is then passed through the second and a third receptacle of the series in succession, the preheated charge of oil being coked

in the second receptacle and the hot vapor mixture from the second receptacle being subjected to a scrubbing operation in the third receptacle during this step of the operation, the hot vapor mixture from the vapor phase cracking operation is then passed through the third and a succeeding receptacle of the series, as through the second and third, and so on, the coke product formed in each of the successive receptacles of the series being discharged when the coking operation in each receptacle is terminated. Oil to be reduced to coke may, with advantage, be supplied to the receptacle in which the scrubbing operation is carried out during each step of the combined operation. In each step of the combined operation, the charge of oil in the receptacle through which the vapors first pass is reduced to coke by the heat of the hot vapor mixture from the vapor phase cracking operation and the hot vapor mixture from this coking operation is freed of entrained material in the scrubbing operation to which this vapor mixture is subjected in the receptacle through which the vapors next pass while the charge of oil in this last mentioned receptacle is at the same time preheated. In the next step of the combined operation this preheated charge of oil, including the constituents separated from the hot vapor mixture discharged from the coking operation in the preceding step, is reduced to coke, so that the combined operation, in accordance with this invention, is carried out without involving transfer of the charge of oil from the receptacle in which the scrubbing and preheating operation is carried out in each step of the combined operation to the preceding receptacle in which the coking operation is carried out in the same step of the combined operation, the coking operation being transferred instead of the successive charges of oil to be reduced to coke. In this respect, the invention has several practical advantages; for example, hot oil pumps for transferring oil from the scrubbing receptacle to the coking receptacle are made unnecessary. In this respect, the invention is of special application in handling stocks containing substantial amounts of solids or semi-solids or of stocks

which break up with the formation of substantial amounts of solids or semi-solids at the temperatures prevailing in the scrubbing operation. The apparatus required is simplified in that the scrubbing operation is carried out in the same receptacles as the coking operation. The coke product formed in the coking operation can, in most cases, be more thoroughly freed of volatile constituents without prejudice to operating economy. Furthermore, the combined operation of the invention, although carried out as a succession of steps, is, over all, made substantially continuous.

The invention will be further described in connection with the accompanying drawing which illustrates, diagrammatically and conventionally, one form of apparatus, in elevation and partly in section with parts broken away, adapted for carrying out the invention, but it is intended and will be understood that the invention can be carried out in other and different forms of apparatus and that this further description is intended as exemplification of the invention.

Referring to the drawing, in carrying out the invention in the apparatus illustrated, the hot vapor mixture from the vapor phase cracking operation carried out in the heater 1, without substantial cooling, is introduced, for example, into the receptacle A in which it is passed through a charge of oil to be reduced to coke and this charge of oil is thereby coked in the receptacle A while the hot vapor mixture from the receptacle A is subjected to a scrubbing operation in the receptacle B by being discharged into and beneath the surface of a liquid body of oil maintained in the receptacle B, this liquid body of oil in the receptacle B being at the same time preheated, when the charge of oil in the receptacle A has been reduced to coke the hot vapor mixture from the vapor phase cracking operation carried out in the heater 1 is introduced into the receptacle B in which it is passed through the preheated charge of oil therein and this charge of oil is thereby coked in the receptacle B while the hot vapor mixture from the receptacle B is subjected to a scrubbing operation in the receptacle C by being discharged into and beneath the surface of a liquid body of oil maintained in the receptacle C, this liquid body of oil in the receptacle C being at the same time preheated; and so on, the coke product formed in each of the receptacles being discharged when the coking operation in each receptacle is terminated. Oil to be reduced to coke may be supplied, for example, to the receptacle B while the hot vapor mixture from the receptacle A is being subjected to a scrubbing operation therein, or to the receptacle C while the hot vapor mixture from the receptacle B is supplied to a scrubbing operation therein, and so on.

The vapor phase cracking operation proper may be carried out, for example, as described in application Serial No. 198,621, filed June 13, 1927, by me, and the hot vapor mixture from the digesting drums discharged directly into the receptacle in which a charge of oil is being reduced to coke, or the digesting drums may be omitted and the hot vapor mixture from the heater proper discharged directly into the receptacle in which a charge of oil is being reduced to coke. In the apparatus illustrated, the vapor phase cracking operation proper is carried out in the heater 1 comprising two groups of series-connected heating tubes arranged in the heating flue of a furnace 8, the oil flowing first through one of the groups of heating tubes countercurrent to the cooler heating gases and then through the other group of heating tubes concurrent to the hotter heating gases, a fan 9 for circulating the heating gases through the heating flue, ducts 10 provided with dampers as shown for recirculating part of the heating gases through the heating flue and for discharging part of the heating gases to the stack 11, a fan 12 and a preheater 13 arranged in the stack 11 for supplying preheated air for combustion to the firebox 14 of the furnace 8. Oil is supplied to the heater 1 through connection 15 and the hot oil products of the vapor phase cracking operation carried out therein are discharged through connection 16.

The coking operation and the scrubbing and preheating operation are carried out in the series of receptacles A, B, C and D. This series of receptacles may include three, four or more receptacles. These receptacles may, for example, be horizontal or vertical drums with suitable means, removable heads or the like, for the discharge of the coke product formed therein. In the apparatus illustrated, the hot vapor mixture discharged from the scrubbing and preheating operation of the combined operation of the invention is discharged through connection 7 to suitable condensing or fractionating and condensing or other recovery apparatus, for example, to recovery apparatus such as that described in application Serial No. 198,621 mentioned above, and that recovery apparatus may be operated, in conjunction with the carrying out of this invention, as described in application Serial No. 198,621 mentioned above. In the apparatus illustrated, by means of connections 20, 21, 22 and 23, connections 24, 25, 26 and 27 and connections 28, 29, 30 and 31 and the valves shown in these connections, the hot vapor mixture discharged from the vapor phase cracking operation through connection 16 may be passed either through receptacles A and B in succession, or receptacles B and C in succession, or receptacles C and D in succession, or receptacles D and A in succession, providing for the carrying out of the in-

vention in these successive pairs of receptacles. By-pass connection 32 is provided to permit the hot vapor mixture from the vapor phase cracking operation to be discharged directly from connection 16 through connection 7. The oil to be reduced to coke is supplied to the receptacle in which the scrubbing operation is carried out, in each step of the combined operation, through connection 19 by means of the valved branches illustrated.

Connection 17 is provided for supplying steam, through the valved branches shown, to the lower ends of the receptacles A, B, C and D and condenser 18 is provided for use when steaming out these receptacles.

In carrying out the invention in the apparatus illustrated, in each step of the combined operation an initial charge of oil less than the total charge of oil to be reduced to coke in the next step of the combined operation may be supplied to the receptacle in which the hot vapor mixture from the receptacle in which the coking is carried out is subjected to a scrubbing operation and additional amounts of this oil supplied to this receptacle during the scrubbing operation to bring this charge of oil to the desired total by the time it is to be subjected to the coking operation in the next step of the combined operation.

In the apparatus illustrated, receptacle A, B, C and D, the vapor lines between them, and connections 16 and 7, are, with advantage, lagged or thermally insulated.

A specific example of an operation embodying the invention as carried out in apparatus of the type illustrated will further exemplify the invention: Fires are started and the heating furnace 8 is brought to operating temperatures while circulating steam through the heater 1 and, for example, receptacle A. The initial charge of oil to be reduced to coke in, for example, receptacle A may be separately preheated and supplied to this receptacle or it may be preheated by circulation through the heater 1 while the heating furnace 8 is being brought to operating temperatures. When the heating furnace 8 has been brought to operating temperatures, the circulation of gas oil or other stock to be subjected to the vapor phase cracking operation through the heater 1 is started. This stock may be a raw gas oil, for example, or an intermediate condensate separated from the vapors discharged through connection 7, for example, or a mixture of the two, for example. By the time the circulation of the stock to be subjected to the vapor phase cracking operation through the heater 1 is started, the receptacle B is filled about one-third full, more or less, with the stock to be reduced to coke, and when the circulation of the stock to be subjected to the vapor phase cracking operation through the heater 1 is started the hot vapor mixture from the vapor phase cracking operation is discharged through the charge of oil to be reduced to coke in the receptacle A and the hot vapor mixture from receptacle A is subjected to a scrubbing operation by being discharged through a liquid body of oil maintained in receptacle B, the hot vapor mixture from receptacle B being discharged through connection 7. During this step of the operation, the stock to be reduced to coke is supplied to the receptacle B at a rate such that this receptacle is approximately full at the end of this step of the operation. When the charge of oil in receptacle A has been reduced to coke and when a sufficient charge of oil has accumulated in receptacle B to be subjected to the coking operation, the hot vapor mixture from receptacle B is passed through a liquid body of oil in receptacle C to which an initial charge of oil has been supplied as previously described in connection with the operation of receptacle B in the preceding step of the combined operation. The hot vapor mixture from the vapor phase cracking operation may be passed through the charge of coke in the receptacle A for some time after the coking operation in receptacle B has been terminated, for example, to assist in stripping this charge of coke of volatile matter. When the charge of coke in receptacle A is sufficiently free of volatile matter, the hot vapor mixture from the vapor phase cracking operation is discharged directly into the receptacle B, the receptacle A is steamed out through condenser 18 and at the termination of the steaming out operation the charge of coke in the receptacle A is removed and this receptacle is cleaned to be ready to receive a charge of oil for carrying out the scrubbing operation during the further step of the combined operation in which a charge of oil is being reduced to coke in the receptacle D. In apparatus such as that illustrated comprising four coking, and scrubbing and preheating, receptacles, each receptacle may, as an example of a convenient and satisfactory operating cycle, be operated on the following schedule, eight hours on the combined scrubbing and preheating operation, eight hours on the coking operation, eight hours on stripping the coke of volatile matter and steaming out, and eight hours on cleaning. In carrying out the combined operation of the invention, the hot vapor mixture from the vapor phase cracking operation may be discharged through connection 16 at a temperature, for example, in the neighborhood of 1100-1120° F., and the hot vapor mixture from the combined operation may be discharged through connection 7 at a temperature in the neighborhood of 650-950° F.

As mentioned above, this invention is of special application in handling stocks containing substantial amounts of solids or semi-solids. The invention is useful, for ex-

ample, in reducing to coke stocks such as crude oils or reduced crude oils including substantial amounts of admixed solid treating agents, lime for example, or such as tank settling, semi fluid mixtures of coke and tar, neutralized acid sludges, and the like.

I claim:

1. In a combined vapor phase cracking and coking operation, the improvement which comprises vaporizing and cracking oil in the vapor phase, then passing the hot vapor mixture from the vapor phase cracking operation through a first and a second receptacle of a series in succession, reducing a charge of oil to coke in the first receptacle and subjecting the hot vapor mixture from the first receptacle to a scrubbing operation in the second receptacle by discharging it into and beneath the surface of a liquid body of oil therein while thereby preheating said liquid body of oil, then passing the hot vapor mixture from the vapor phase cracking operation through the second and a third receptacle of the series in succession, reducing the preheated charge of oil to coke in the second receptacle and subjecting the hot vapor mixture from the second receptacle to a scrubbing operation in the third receptacle by discharging it into and beneath the surface of a liquid body of oil therein while thereby preheating said liquid body of oil, and discharging coke from the first receptacle, then passing the hot vapor mixture from the vapor phase cracking operation through the third and a succeeding receptacle of the series, as through the second and third, supplying oil to be reduced to coke to the third receptacle during this step of the combined operation, then passing the hot vapor mixture from the vapor phase cracking operation through the third and a succeeding receptacle of the series, as through the second and third, supplying oil to be reduced to coke to said succeeding receptacle of the series during this step of the combined operation, and discharging coke from the second receptacle, and so on, retaining the charge of oil in the receptacle in which the scrubbing and preheating operation is carried out in each step of the combined operation in that receptacle.

by discharging it into and beneath the surface of a liquid body of oil therein while thereby preheating said liquid body of oil, and discharging coke from the first receptacle, supplying oil to be reduced to coke to the third receptacle during this step of the combined operation, then passing the hot vapor mixture from the vapor phase cracking operation through the third and a succeeding receptacle of the series, as through the second and third, supplying oil to be reduced to coke to said succeeding receptacle of the series during this step of the combined operation, and discharging coke from the second receptacle, and so on, retaining the charge of oil in the receptacle in which the scrubbing and preheating operation is carried out in each step of the combined operation in that receptacle.

In testimony whereof I affix my signature. 85
HARRY L. PELZER.

2. In a combined vapor phase cracking and coking operation, the improvement which comprises vaporizing and cracking oil in the vapor phase, then passing the hot vapor mixture from the vapor phase cracking operation through a first and a second receptacle of a series in succession, reducing a charge of oil to coke in the first receptacle and subjecting the hot vapor mixture from the first receptacle to a scrubbing operation in the second receptacle by discharging it into and beneath the surface of a liquid body of oil therein while thereby preheating said liquid body of oil, supplying oil to be reduced to coke to the second receptacle during this step of the combined operation, then passing the hot vapor mixture from the vapor phase cracking operation through the second and a third receptacle of the series in succession, reducing the preheated charge of oil to coke in the second receptacle and subjecting the hot vapor mixture from the second receptacle to a scrubbing operation in the third receptacle
